CLAIM

I claim the design of case for a media storage disk, as shown and described.

DESCRIPTION

FIG. 1 is a top perspective view showing my new design for a case for a media storage disk;

FIG. 2 is a bottom perspective view;

FIG. 3 is a top plan view;

FIG. 4 is a bottom plan view;

FIG. 5 is a left side elevational view;

FIG. 6 is a right side elevational view;

FIG. 7 is a rear elevational view;

FIG. 8 is a front elevational view;

FIG. 9 is a perspective view showing the case in an open position;

FIG. 10 is a top plan view of FIG. 9; and,

FIG. 11 is a left side elevational view of FIG. 9, the right side being a mirror image.
